UNITED STATES PATENT OFFICE.

FLOYD B. GROFF, OF ST. JOHNSVILLE, NEW YORK.

TEAT-CUP.

No. 878,057.

Specification of Letters Patent.

Patented Feb. 4, 1908.

Application filed July 8, 1907. Serial No. 381,892.

To all whom it may concern:

Be it known that I, FLOYD B. GROFF, a citizen of the United States, residing at St. Johnsville, in the county of Montgomery and State of New York, have invented certain new and useful Improvements in Teat-Cups, of which the following is a specification.

My invention relates to milking devices, and consists in a teat-cup with its combinations.

The object of my invention is to produce a teat-cup that will fit closely around the teat so as not to allow any air to pass between the cup and the teat. The cup is so constructed as to support the teat for its entire length, so as not to make it sore by use, and a cup so constructed that its several parts may be easily and quickly taken apart to be cleaned, and as easily and as quickly assembled.

In the accompanying drawings, Figure 1, is a side elevation of my teat-cup, the shut-off being in position, the lower end of the tapering tube being in section to show the position of the shut-off when in place. Fig. 2, is a sectional view of the mouth of the tube and the threaded binding-ring. Fig. 3, is a sectional view of the binding-cap. Fig. 4, is a perspective view of the mouth-piece. Fig. 5, is a perspective view of a wrench used in connection with my invention.

My invention is described as follows:—

The numeral 1, represents the tapering tube, provided at its lower end with a bead 2, or other suitable provision for connecting the tube with the suction-pipe of the milking machine.

The form and size of the tapering tube and the mouth-piece are such that the teat is supported therein from its tip to its base.

As teats differ considerably in size and form in different cows, these tubes and mouth-pieces can be made different sizes so as to fit different size teats.

The upper end of the tube enlarges into a bowl 3, and at its extreme upper end turns squarely out at right angles, forming a horizontal flange 4, and fitting around the upper end of said bowl is a threaded ring 5, the threads being on the outer surface of the ring.

The mouth-piece is made of some flexible

material, and consists in an annular ring 6, having extending from its base a horizontal flange 7, and extending downwardly from the lower edge of the ring is an apron 8. 55 This mouth-piece fits in said bowl 3, the apron thereof extending downwardly into said bowl, its flange 7, fitting on the flange 4, of the bowl 3, the annular ring extending upwardly.

Screwing down on the threaded ring 5, and securely clamping the horizontal flange 7, against the upper face of the flange 4, is a cap 9, leaving the upper edge of the ring 6, extending upwardly some little distance above the upper face of said cap. As the threaded ring 5, is not integral with nor permanently secured to the flange 4, but is so constructed that it may be removed for the purposes above mentioned, it is provided in 70 its lower face with two holes 10, one immediately opposite the other; and I use in connection with said ring 5, a wrench 11, for screwing said ring into place, and unscrewing it when desired, and for holding it and 75 keeping it from turning when I screw on the cap.

I use, in connection with my invention, a shut-off 12, for the purpose of shutting off any teat-cup in milking a cow that has not 80 as many teats as the suction-pump provides for, or when it is not advisable to use all the teats on the udder.

Although I have specifically described the combination, construction and arrangement of the several parts of my invention I do not confine myself particularly to such specific combination, construction and arrangement, as I claim the right to make such changes and modification therein as may 90 clearly fall within the scope of my invention, and which may be resorted to without departing from the spirit, or sacrificing any of my patentable rights therein.

Having described my invention, what I 95 claim as new and desire to secure by Letters Patent, is:—

A teat-cup, consisting of a tapering tube, terminating at its upper end in a bowl and horizontal flange; a threaded ring, fitting 100 around said bowl under said flange; a mouth-piece, consisting of an annular ring,

a horizontal flange and an apron, said mouth-piece fitting into said bowl with its flange resting on said horizontal flange, and a threaded cap, fitting down on said flange and screwing on said ring, substantially as shown and described and for the purposes set forth.

In testimony whereof I affix my signature, in presence of two witnesses.

FLOYD B. GROFF,

Witnesses:

LAURIN BEEKMAN,
FRED D. STORMS.
